LAMP

Anton J. Yeager, Wisconsin Rapids, Wis., assignor
to Prentiss-Wabers Products Co., Wisconsin
Rapids, Wis., a corporation of Wisconsin

Application April 27, 1936, Serial No. 76,506

14 Claims. (Cl. 67—50)

The present invention relates to hydrocarbon fuel burning devices, and more in particular to lamps or lanterns having a fuel combusting burner supplied with hydrocarbon fuel under pressure.

Among the objects of the present invention is to provide a novel lamp or lantern of the type disclosed wherein the various elements of construction are so arranged as to provide a sturdy lamp or lantern structure and which may be manufactured at a relatively low cost.

The present invention more particularly includes as an object the idea of providing a lamp or lantern wherein the globe or chimney is protected against breakage because of rough handling, which protection is effected by means of a novelly arranged frame support which serves as a mounting for the hood, which in turn serves to support the manifold for mixing the combustible fuel with combustion supporting material, such as air or the like.

Still another object within the purview of the present invention is to provide a novel lamp or lantern wherein the supporting frame embracing the chimney or globe provides a support for the hood and also a connecting medium for a bail. More particularly, the bail may engage with the supporting frame or hood, or both, and is provided with inwardly extending portions serving to prevent displacement of the chimney or globe.

Still another object of the present invention is to provide a novel supporting frame for a hood, in combination with means cooperating with the hood for preventing displacement of the hood in respect to the frame, such means permitting the ready and easy assembly of the hood into and out of its operative position with respect to the supporting frame.

The present invention also contemplates the idea of supporting the manifold by the hood and free from the fuel generator which supplies vaporized hydrocarbon fuel thereto. More particularly, the present invention discloses the idea of supporting the manifold by the hood, which in turn is supported by a supporting frame and the fuel generator being normally spaced from but projecting into the manifold for supplying the vaporized fuel.

Still a further object of the present invention is to provide a manifold for a lamp or lantern of the type herein disclosed, which is so constructed as to efficiently mix vaporized hydrocarbon fuel with a combustion supporting medium, and which is formed with a mantle support and an air intake conduit, either or both of which may be formed

integrally with the main portion of the manifold, or as separate elements.

Other objects, features, capabilities and advantages are comprehended by the invention, as will later appear and as are inherently possessed thereby.

Referring to the drawing:

Figure 1 is a view partly in elevation and partly in cross section of a lantern made in accordance with the present invention;

Figure 2 is a fragmentary view in cross section taken in a plane of ninety degrees to the plane of Figure 1, disclosing the lantern thereof;

Figure 3 is a fragmentary view in cross section taken in the plane represented by line 3—3 of Figure 2 of the drawing; and

Figure 4 is a detached view in elevation of a part of the lamp frame showing the construction thereof more in detail.

Referring now more in detail to the drawing, an embodiment selected to illustrate the present invention is shown as comprising a lantern provided with a hollow base or receptacle 2 for retaining a quantity of hydrocarbon fuel 4, such as gasoline or the like, which may be introduced into the receptacle through an opening normally closed by a screw threaded cap or plug 6 which forms a fluid tight joint with the receptacle. Mounted in the receptacle 2 is a pump 8 provided with a plunger 10 and a discharge tube or conduit 12 which terminates within the air chamber 14 of the receptacle 2 above the level of the fuel 4, this pump being provided, as is well known, for compressing the air within the chamber 14 to force the hydrocarbon fuel through the intake 16 of a fuel vaporizing mechanism, generally referred to as 18, which may be connected as at 20 to the top of the receptacle 2 and comprises valve means 22 substantially horizontally disposed from which a generator 24 extends upwardly, this valve and generator mechanism being of the usual construction for vaporizing fuel from the receptacle and controlling the flow thereof. The valve mechanism is provided with an upstanding boss 26 to which is connected a supporting frame, generally referred to as 28, this supporting frame including the perforated base 30 which is secured to the boss by means of the screw 32 threaded in the boss 26 and which draws the base into rigid engagement with the boss, the base being further supported outwardly of the connection to the boss by means of a perforated substantially cylindrical member 34 disposed between the base and the top of the receptacle 2, this member 34 being provided with suitable openings for the valve mechanism

The supporting frame further includes a plurality of upwardly extending supports, such as 36 and 38, which, as disclosed in the embodiment selected to illustrate the present invention, are oppositely disposed and connected adjacent their lower ends to the base as by means of rivets or the like 40. As shown in the drawing, the upright supports are disposed exteriorly of a chimney or globe 42 which is supported on the base 30 and retained adjacent its lower end against lateral displacement by the upstanding flange 44 of the base. These upright supports are connected adjacent their upper ends by a substantially circular band 46 which embraces the upper end of the globe or chimney 42. The upper ends of the upright supports extend upwardly through oppositely disposed openings 48 and 50 of a hood 52 supported upon the frame 28 at the band member 46, each of these upper ends being formed to provide an upwardly extending ear 56 provided with the enlarged aperture 57. The apertures in the ears 56 are aligned with suitable apertures or openings 58 formed in the upstanding wall 60 of the hood 52, these aligned apertures being adapted to receive the inwardly extending portions 62 and 64 of a bail 66 which is used for transporting the lamp or lantern from place to place and to support the same when it is desired to suspend the lantern from a support or the like. These inwardly extending portions 62 and 64 are provided with the bumps or protuberances which are adapted to pass through slots 63 communicating with the apertures 57 of the ears whereby said portions 62 and 64 are received within the aligned openings 35 of the ears and hood in one position of the handle, the handle being locked in position by the protuberances 68 when assembled therewith as shown in the drawing. Furthermore, as clearly evidenced in the drawing, these portions 62 and 64 extend over the upper edge of the chimney or globe 42, which fits within the wall 60 of the hood, to limit upward displacement thereof in the supporting frame 28.

As disclosed in the drawing, the hood 52 normally is supported by the frame 28 at the band 46 and is held against upward displacement by means of the portions 62 and 64 of the bail. The hood 52 may be inserted in supporting relation with the support 28 by bringing the openings 48 and 50 into register with the apertured ears 56 and moving the same downwardly thereover onto the band 46. The hood is then locked in position by the bail 66 as indicated.

Although the supporting members 36 and 38 are shown as being formed with the ears 56 for holding the hood in position, it is to be understood that any suitable means could be provided in lieu thereof for effecting the same results. It is also to be noted that although in the present disclosure the bail portions 62 and 64 engage with both the ears and the hood 52, nevertheless, if desired, this bail, hood and supporting means 36 and 38 may be so formed and arranged that the bail portions 62 and 64 may engage the hood or the ears only.

The hood is provided with an apertured wall member 70 upon which is disposed a top member 72 serving as a support for a manifold 74. This manifold 74 is secured to the hood by means of a screw threaded member 76 connected to the top of the same and which is adapted to extend upwardly through a non-circular opening 78 provided in the member 72. Threaded on the member 76 is a lock nut 80 which is received within the opening 78 and engages member 72 to prevent

relative movement between the manifold and the member 72 when the manifold is locked in supporting relation with respect thereto. This locking of the manifold to the member 72 is effected by means of a nut 82 provided with an eyed portion 84 which may be threaded onto the end of member 76. A metal washer 86 and a washer 88, preferably of fire resisting material, are disposed between the nut 82 and the member 72 to permit drawing of the manifold 74 upwardly into engagement with the member 72 upon rotation of nut 82.

The manifold 74 is provided with a passageway 90 adapted to communicate with an intake conduit 92 which is threaded at its upper end to the manifold and depends therefrom and has its lower end extending through an opening 94 provided in the base 32. This passageway 90 also communicates with the opening 96 which loosely receives the upper end of the generator 24, which generator is provided with the jet 98 adapted to discharge vaporized hydrocarbon fuel into passageway 90 where it is initially mixed with air passing up through the intake conduit 92 for supporting combustion. This mixture of vaporized hydrocarbon fuel and air passes through the passageway 90 into a mixing chamber 100, where the same is intimately mixed. This mixing chamber 100 communicates through passageway 102 which is formed at its lowermost end with a mantle support 104 upon which is secured a mantle of the usual construction adapted to receive and burn the vaporized fuel for lighting purposes.

From the above description it will be seen that the manifold, together with the air intake conduit 92, is directly supported by the hood and is entirely free with respect to the supporting relation of the generator 24. This manifold is accordingly supported by the frame 28 through the hood 52 and not by the generator. Although the mantle support 104 is shown as formed integral with the main portion of the manifold, nevertheless if desired the same can be formed as a separate unit and secured in any desired manner to the manifold. Furthermore, although the air intake conduit 92 is disclosed as being formed as a separate member threaded to the manifold, nevertheless the construction of the manifold is such that this conduit can be formed as an integral part of the manifold.

In order to move the hood in respect to the support 28 as above described, it is necessary to remove the nut 82 and washers 86 and 88. This permits the hood to be removed over the upper end of the screw threaded member 76, and at this time the manifold will be held by engagement thereof with the generator 24 and the engagement of the conduit 92 with the base or valve mechanism 18. Upon moving the hood again into position over the screw threaded member 76, the manifold is moved into a position to be supported by the hood upon rotation of the nut 82 into tightened position.

The present invention also comprehends novel structure incorporated in the lamp as shown in the drawing whereby fuels such as kerosene and the like may be initially volatilized for mixing with a combustible material when the lamp or lantern is first lighted. Such structure comprises a priming cup 110 having a centrally disposed opening 112 arranged to slide over the generator 24. This priming cup 110 may be secured to the intake conduit 92 in any desired manner, as by welding or a screw connection, and as shown in the drawing, the cup 110 has the upwardly extending bracket 114 secured as by means of

screw 116 to the intake conduit 92. This priming cup is adapted to receive and hold hydrocarbon fuel which may be introduced into the same through an opening 118 formed in the chimney 5 42. As is well understood, when the priming fuel in the cup is ignited and lighted the heat generated thereby volatilizes the fuel and air under pressure in the generator 24 whereby the mixture thereof is in proper condition for introduction into 10 the manifold. It is to be noted that the priming cup 110 which is secured to the intake conduit 92 serves as a guide therefor when the manifold is being inserted into place.

While I have herein described and upon the 15 drawing shown an illustrative embodiment of the invention, it is to be understood that the invention is not limited thereto but may comprehend other constructions, arrangements of parts, details and features without departing from the 20 spirit of the invention.

I claim:

1. In a lamp, the combination of a fuel receptacle, a frame having a base supported by said receptacle, a hood supported by said frame, a 25 manifold supported by said frame through said hood, said manifold having an air intake conduit extending downwardly and projecting through said base and free from supporting relation therewith and a mantle supporting means having a 30 passage communicating with the chamber of said manifold, and a fuel discharge member supported by said receptacle for discharging fuel from said receptacle and into said manifold.

2. In a lamp, the combination of a fuel receptacle, valve means mounted on said receptacle and having communication with the fuel in said receptacle, a frame having a base mounted on 35 said valve means, a hood supported by said frame, a manifold supported by said frame, said manifold having an air intake conduit extending downwardly and projecting through said base and free from supporting relation therewith and a mantle supporting means having a passage communicating with the chamber of said manifold, and a fuel 40 discharge member supported by said valve means and extending upwardly through said base therefrom, said discharge member extending into and being loosely embraced by said manifold for discharge of fuel into the same.

3. In a lamp, the combination of a frame having a base, a globe supported on said base, said frame including a plurality of supports extending upwardly from said base exteriorly of said globe, a frame member embracing said globe and being connected to said supports in spaced relation to said base, a hood supported on said member, and a manifold connected to and supported by said hood, said manifold having an air intake conduit depending therefrom within said globe 55 and extending through an opening in said base and being free from supporting relation therewith.

4. In a lamp, the combination of a frame having a base, a globe supported on said base, said frame including a plurality of supports extending upwardly from said base exteriorly of said globe, a frame member embracing said globe and being connected to said supports in spaced relation to said base, a hood supported on said member and being provided with apertures, said supports extending through the apertures of said member and being provided with apertures, and a bail 60 extending through oppositely disposed apertures of said supports.

5. In a lamp, the combination of a frame hav-

ing a base, a globe supported on said base, said frame including a plurality of supports extending upwardly from said base exteriorly of said globe, a frame member embracing said globe and being connected to said supports in spaced relation to 5 said base, a hood supported on said member and having oppositely disposed apertures, and a bail extending through said apertures and over the upper edge of said globe thereby preventing its displacement.

6. In a lamp, the combination of a frame having a base, a globe supported on said base, said frame including a plurality of supports extending upwardly from said base exteriorly of said globe, a frame member embracing said globe and being connected to said supports in spaced relation to 15 said base, said supports extending above said member and being provided with apertures, a hood supported on said member and having apertures aligned with said first-named apertures, 20 and a bail extending through said apertures and over the upper edge of said globe thereby preventing its displacement.

7. In a lamp, the combination of a frame having a base, a globe supported on said base, said frame including a plurality of supports extending upwardly from said base exteriorly of said globe, a frame member embracing said globe and being connected to said supports in spaced relation to 25 said base, a hood supported on said member and having apertures, said supports extending through certain of said apertures and being provided with apertures disposed in alignment with other apertures of said hood, and a bail engaging oppositely disposed aligned apertures.

8. In a lamp, the combination of a frame having a base, a globe supported on said base, said frame including a plurality of supports extending upwardly from said base exteriorly of said globe, a frame member embracing said globe and being connected to said supports in spaced relation to 30 said base, a hood supported on said member and having apertures, said supports extending through certain of said apertures and being provided with apertures disposed in alignment with other apertures of said hood, and a manifold supported by said hood, said manifold having an air intake conduit depending therefrom and having an inlet adjacent said base and a mantle support disposed substantially centrally in respect to 35 said globe.

9. In a lamp, the combination of a frame having a base, a globe mounted thereon, said frame including upright supports exteriorly of said globe, a frame member embracing said globe disposed 40 adjacent the upper ends of said supports, a hood supported on said frame and being provided with apertures, said supports having end portions extending above said member and through said apertures, a bail connected to said end portions, 45 and a manifold supported by said hood, said manifold having an air intake conduit depending therefrom and having an inlet adjacent said base and a mantle support disposed substantially centrally 50 in respect to said globe.

10. In a lamp, the combination of fuel feeding means comprising a generator, a manifold associated therewith and including an air intake conduit, and a priming receptacle secured to said conduit and slidably embracing said generator.

11. In a lamp, the combination of fuel feeding means comprising a generator, a manifold associated therewith and including an air intake conduit, a chimney embracing said feeding means, and a priming receptacle secured to said conduit

and slidably embracing said generator, said chimney having an opening for access to said priming receptacle.

12. In a lamp, the combination of fuel feeding means comprising a generator, a manifold associated therewith and having a conduit for introduction of a combustion supporting medium into said manifold, and a priming receptacle secured to said conduit and adapted to slidably receive said generator.

13. In a lamp, the combination of a fuel receptacle, fuel feeding means associated therewith and having a generator extending therefrom, a frame supported by said receptacle, a manifold including a conduit for introduction of a combustion supporting medium into the same sup-

ported by said frame, a chimney supported by said frame surrounding said generator and manifold, and a priming receptacle secured to said conduit and having an opening embracing said generator serving to guide said conduit when said manifold is placed in position, said chimney having an opening for access to said priming receptacle.

14. In a lamp, the combination of fuel feeding means comprising a generator, a manifold associated therewith and including an air intake conduit, and a priming receptacle secured to said conduit and provided with inner and outer up-standing walls, said inner wall defining an opening for slidably receiving said generator. 15

ANTON J. YEAGER.
